(57) **CLAIM**

The ornamental design for a consecutive shooting target, as shown and described.

DESCRIPTION

FIG. 1 is a perspective front view of the invention in silhouette configuration;

FIG. 2 is a straight side view thereof;

FIG. 3 is a straight front view thereof;

FIG. 4 is a straight rear view thereof;

FIG. 5 is a close up perspective view thereof; and,

FIG. 6 shows a perspective view of the invention in a round target configuration.

Dashed lines are used to show the environment and other shading lines are used, neither of which comprise any of the claimed invention.
